ELECTRIC SWITCH

Vincent W. Leonard, Saugus, Mass., assignor to
General Electric Company, a corporation of
New York

Application August 25, 1933, Serial No. 686,708

5 Claims. (Cl. 200—67)

My invention relates to improvements in electric switches and more particularly to improvements for switch operating mechanisms for electric switches of the so-called over-center snap action type. An object of my invention is to provide an improved switch mechanism which is compact and which is free of latches and does not require a large number of springs. Another object of my invention is to provide an improved switch mechanism which may be double-throw and which after movement from one contact controlling position to another automatically returns to its initial contact controlling position. A further object of my invention is to provide an improved switch mechanism which is operative to insure the desired contact operation and pressure with a minimum effort.

My invention will be better understood from the following description when considered in connection with the accompanying drawing and its scope will be pointed out in the appended claims.

In the accompanying sheet of drawing, Fig. 1 illustrates in perspective an electric switch embodying my invention; Fig. 2 is a side elevation of the switch shown in Fig. 1 with the parts in the same circuit controlling position; and Fig. 3 is a side elevation of the switch shown in Fig. 1 with the parts in another circuit controlling position.

In the illustrated embodiment of my invention, a suitably mounted support 5 has pivotally associated therewith two movable members 6 and 7 which extend from the support in opposite directions as shown. While the support 5 may be in the form of a cylindrical pivot on which the members 6 and 7 are rotatably mounted, I preferably use, in order to reduce friction to a minimum and also for simplicity in construction and assembly, a support such as shown, which presents suitable knife edges on which the members 6 and 7 are fulcrumed. These members may thus be termed rocker members. For limiting the movement of the members 6 and 7 in each direction there are provided suitable means such as stops 8 and 9 for the member 6, and 10 and 11 for the member 7.

Either one or both of the stops 10 and 11 may take the form of contacts, as shown, depending upon whether it is desired to have a single or double-throw switch and a cooperating contact 12 is mounted on the member 7.

For moving the members 6 and 7 toward and holding them against first the stops 8 and 10 respectively and then the stops 9 and 11 respectively, I provide an over-center biasing means such as the spring 13 which interconnects the members 6 and 7.

For actuating the switch mechanism, I provide an operating member 14 which may, for simplicity in construction, be pivotally mounted on one of the stops 9 and have its motion in one direction, clockwise as shown in the drawing, limited by another stop, for example the stop 8.

In order that movement of the operating member in either direction may move the over-center biasing means 13 over center so as to move the member 7 from one contact controlling position to another, I provide a resilient force transmitting means, such as the spring 15, which interconnects the operating member 14 and the rocker member 6. In order that the movement of the operating lever may be as small as possible, the spring 15 is preferably connected to the operating lever at a point relatively close to the fulcrum of the rocker 6. The spring 15 is so arranged with respect to the support 5, the rocker member 6 and the operating member 14 as to tend to maintain the parts in the position shown in Fig. 1 and in full line in Fig. 2, but upon a predetermined movement of the operating member in one direction, counter-clockwise as shown in the drawing, to actuate the rocker member 6 about its fulcrum 25 in a direction, clockwise as shown in the drawing, to move the over-center spring 13 across the axis of the support 5 whereby to effect movement of both of the members 6 and 7 from one limiting or contact controlling position, shown in Figs. 1 and 2, to another limiting or contact controlling position, shown in Fig. 3. On release of the operating member, however, the spring 15 moves the operating member and the rocker member 6 in directions opposite to their preceding movements thereby moving the over-center spring 13 back across the axis of the support 5 so as to return the movable members 6 and 7 to their first contact controlling position.

The operation of the spring 15 will be more clearly apparent from Figs. 2 and 3. Thus, referring to Fig. 2 with the parts shown in the full line position, it will be apparent that the axis of the over-center spring 13 is below the axis of the fulcrum 5. Consequently, the pull of the spring 13 holds the members 6 and 7 against their stops 8 and 10 respectively. The pull of the spring 15 on the operating member 14 is such as to exert a torque tending to turn the operating member clockwise about its pivotal support 9, thus maintaining the operating member against the stop 8 because the point of attachment of the spring 15 to the operating member 14 is below the pivot 9. Also the pull of the spring 15 on the rocker arm 6 is in such a direc-

tion as to produce a torque tending to turn the rocker member 6 counter-clockwise about its fulcrum. The member 6 is thus maintained against the stop 8. The spring 15 may be a stronger spring than the spring 13, that is to say, it may require a greater force to stretch it a given length. As the operating member is rotated counter-clockwise by any suitable means, such as cams 17 rotating in the direction indicated by the arrow 18, the spring 15 is raised above the axis of the fulcrum 5. Immediately this occurs the force of the spring 15 on the member 6 is in such a direction as to produce a torque tending to turn this member clockwise about its fulcrum, but no clockwise movement of the member 6 occurs until this clockwise torque exceeds the counter-clockwise torque of the spring 13 on the member 6. After the member 6 has turned clockwise a predetermined amount, the over-center spring 13 is carried above the axis of the support 5. The force of the over-center spring then is directed on both of the members 6 and 7 in such a way as to bring them to bear against their respective stops 9 and 11, as shown in Fig. 3.

In this position, however, the force exerted by the spring 15 on the operating member 14 is such as to produce a torque tending to turn the operating member clockwise about its pivot 9 to engage the stop 8 because the point of attachment of this spring to the member 14 is still below the pivot 9. Although the force exerted by the spring 15 on the member 6 is in a direction to produce a torque tending to hold the member 6 against its stop 9, the torque on the operating member 14 is enough greater so that when the cam 17 releases the operating member 14, this member moves clockwise to carry the spring 15 below the axis of the support 5. As soon as this occurs, the torque exerted by the spring 15 on the member 6 is in such a direction as to tend to turn the member 6 counter-clockwise. When this counter-clockwise torque exceeds the clockwise torque of the spring 13 on the member 6, this member rotates and carries the over-center spring 13 below the axis of the support 5 whereupon both of the members 6 and 7 are returned to the initial contact controlling position. In other words, the second contact controlling position is maintained only for the period of time that the operating member is held in the position illustrated in Fig. 3 and the initial contact controlling position is immediately restored upon release of the operating member.

While the operating member 14 can be operated in any way suitable to the purpose at hand, I have illustrated an arrangement which may be used in circuit controlling devices employed in connection with reclosing circuit breaker schemes wherein a graduated time disk 19 is provided with a plurality of adjustably positioned cams 17 which may be driven through a gear mechanism 21 by any suitable motor means 20, electric or otherwise.

While I have shown and described my invention in considerable detail, I do not desire to be limited to the exact arrangements shown but seek to cover in the appended claims all those modifications that fall within the true spirit and scope of my invention.

What I claim as new and desire to secure by Letters Patent of the United States is:

1. A switch operating mechanism comprising a support, two movable members pivotally associated with said support and extending therefrom in opposite directions, means for limiting the

movement of each member in each direction, over-center biasing means for moving said members toward and holding them against the motion limiting means, an operating member, means for actuating said operating member in one direction and resilient force transmitting means interconnecting said operating member and one of said movable members for actuating the movable member to move said biasing means over center on movement of the operating member in said direction whereby to effect movement of both movable members from one motion limiting position to the other motion limiting position, said resilient means being connected to said operating member and to said one of said movable members at points such as continuously to exert a force tending to move the operating member in the opposite direction whereby to return said movable members to the first motion limiting position after a definite movement of said actuating means.

2. A switch operating mechanism comprising a support, two movable members pivotally associated with said support and extending therefrom in opposite directions, a contact carried by one of said members, means for limiting the movement of each member in each direction, the motion limiting means of the contact carrying member being contacts engageable by the contact on the member, over-center biasing means for moving said members toward and holding them against the motion limiting means, an operating member means for actuating said operating member in one direction and resilient force transmitting means interconnecting said operating member and the other one of said movable members for actuating the movable member to move said biasing means over center on a predetermined movement of the operating member in said direction whereby to effect movement of the movable contact carrying member from an initial position against the contact on one side to the contact on the other side, said resilient means being connected to the operating member and to said other movable member at points such as continuously to exert a force tending to move the operating member in the opposite direction whereby to return said movable contact carrying member to its initial position after a definite movement of said actuating means.

3. A switch operating mechanism comprising a support, two rocker members fulcrumed on said support, stops on opposite sides of said members for limiting the angular movement of each in each direction, an over-center spring interconnecting said members for moving said members toward and holding them against the stops on their respective sides, an operating member pivotally associated with one of said stops, a spring interconnecting said operating member and one of said rocking members for actuating the rocking member to move said biasing means over center on movement of the operating member whereby to effect movement of both rocker members from their positions against the stops on one side to the stops on the other side.

4. A switch operating mechanism comprising support, two movable members pivotally associated with said support and extending therefrom in opposite directions, means for limiting the movement of each member in each direction, over-center biasing means for moving said members toward and holding them against the motion limiting means, an operating member, means interconnecting one of said movable members

with said operating member for biasing each to a predetermined position the points of connection of said biasing means being such as to cause the biasing means to effect movement of said one movable member in a direction to move said over-center biasing means over center upon a predetermined movement of the operating member in one direction whereby to effect movement of both movable members from one limiting 10 position to another and on release of the operating member to move both the operating member and said one movable member in the opposite direction whereby to move the over-center biasing means back over center to return the movable members to their first limiting position.

5. A switch operating mechanism comprising a support, two rocking members fulcrumed on said support, stops on opposite sides of said members for limiting the movement of each in each

direction, resilient over-center means interconnecting said members for moving the members toward and holding them against said stops, an operating member pivotally associated with one of said stops and movable in one direction to engage another of said stops and resilient means interconnecting said operating member and one of said rocker members for biasing each toward said other stop operative on a predetermined movement of the operating member in another 10 direction to move said over-center biasing means over center whereby to effect movement of both rocker members from one limiting position to another and on release of the operating member to effect a return movement thereof to said other stop whereby to move said over-center biasing means back over center to return the rocker members to their first limiting position.

VINCENT W. LEONARD.
